UNITED STATES PATENT OFFICE.

ROBERT G. MUELLER, OF PHILADELPHIA, PENNSYLVANIA, ASSIGNOR OF
ONE-HALF TO HERMANN HESSENBRUCH, OF SAME PLACE.

SLICING-MACHINE AND FEED MECHANISM.

SPECIFICATION forming part of Letters Patent No. 626,764, dated June 13, 1899.

Application filed February 25, 1898. Serial No. 671,555. (No model.)

To all whom it may concern:

Be it known that I, ROBERT G. MUELLER, a citizen of the United States, residing in the city and county of Philadelphia, State of Pennsylvania, have invented a new and useful Improvement in Feed-Motions for Slicing and other Machines, which improvement is fully set forth in the following specification and accompanying drawings.

10 My invention consists of a feed-motion for a slicing or other machine, the same embodying a traveler or pushing device which is operated by the traction of a reciprocating rod or shaft on which said traveler is freely mounted, said traction being effected by the operation of a movable member, the traveler receiving motion at intervals from said reciprocating shaft in only advance direction, the construction of said parts avoiding the employment of a rack or toothed bar to effect said advance of the traveler.

Figure 1 represents a side elevation of a slicing-machine embodying my invention. Fig. 2 represents a partial plan view and a 25 partial horizontal section thereof. Figs. 3 and 4 represent front views of different portions thereof. Figs. 5, 6, 7, 8, 9, and 10 represent views of detached parts, on an enlarged scale, the same being partly in elevation and 30 partly in section. Fig. 11 represents a perspective view of one of the cams.

Similar letters of reference indicate corresponding parts in the figures.

Referring to the drawings, A designates a 35 rotatable cutter, the same consisting of the circular or other shaped frame B and the blades C, secured thereto, said frame being mounted by its rim D on the stationary open frame E, the latter having peripheral rims F and G, between which the rim D of the frame B is adapted to rotate. Interposed between the rims F and G and the rim D are balls H and J, which are freely seated in grooves in said rims, thus providing ball-bearings for said 45 rims, whereby the cutter rotates with great freedom and smoothness.

K and L designate rods or shafts whose surfaces are untoothed or preferably smooth and which are mounted at one end on the frame 50 E and at the other end on the bracket M, the rod K being stationary and the rod L being movable in the direction of its length both on the frame E and bracket M, it having on the

end adjacent to the frame E the shoulders N and P, which are adapted to be engaged at 55 intervals by the cams Q Q', which are mounted on the bolt Q' at the center of the cutter, whereby advance and return motions will be imparted to said rod L for purposes to be hereinafter explained.

R designates a traveler, which consists of a body formed with eyes S S', through which the rods K and L freely pass, said rods thus supporting said traveler and permitting the latter to slide thereon toward and from the knife, 65 said traveler carrying the hanger T, which freely enters the trough U, the latter being supported on the lower portions of the bracket M and frame E and extending parallel with the rods K and L below the same, the forward 70 end of said trough being open and located near the back of the cutter A, so that as the traveler advances it carries the hanger T with it, and the material to be sliced or cut, placed in the trough U, is presented to the blades of 75 the cutter.

On the rods, between the eyes S S' of the traveler, are the annuli V, which freely embrace said rods and have tongues W on the inner sides thereof, said tongues abutting 80 against the shoulder X within the traveler, the adjacent faces of the eyes S being oblique to permit the annuli to be pressed against them in similar direction, as most plainly shown in Figs. 5 and 8. Bearing against the 85 annuli are the springs Y, whereby they occupy oblique positions on or acute angles to the rods, and their inner peripheries bite the surfaces of said rods, so as to take firm hold thereof.

The tongues W of the annuli have bearing 90 against them the lower limb of the lever Z, which is mounted on the traveler, so that when said lever is operated it bears against the tongues W and presses them forwardly, whereby the annuli are moved from their oblique positions to those of a right angle, or nearly so, whereby their bite on the rods is overcome, and the traveler may be run back on the rods without interference of the annuli.

The operation is as follows: The trough is supplied with an article to be sliced—whether bread, smoked or dried beef, or other food—the hanger being removed from the cutter the length of said article. The cutter is rotated 105 and advancing motion imparted to the rod L

by the action of the cam Q against the shoulder N. Owing to the bite of the annulus on said rod the traveler is coupled by said annulus with said rod and so advances with the latter the distance of motion imparted to the rod, and with it the hanger T, which, pressing against the article in the trough, moves it a relative distance to the cutter and beyond the same the thickness of the slice to be removed from said article. Then the cam Q' acts on the shoulder P and forces back the rod L, it then sliding freely through the annulus, as the latter then has no biting action on said rod. The traveler is now at rest; but when the rod is again advanced the annulus once more bites or grips said rod, and the traveler receives further motion, and with it the hanger, so that the article is moved a further extent and a fresh surface of said article presented to the cutter. Projecting rearwardly from the frame E is a bolt E', which is so disposed that it is in the path of the upper end or handle portion of the lever Z, so that when the carrier has advanced to full extent said lever strikes said bolt and releases the annulus S, whereby the feeding motion ceases and the hanger T is prevented from being engaged by the cutter. Owing to the screw or bolt Q², which carries the cams Q Q', the latter may be adjusted with precision relatively to the shoulders P on the rod L for cutting different thicknesses. In the present case the feed is occasioned twice to one rotation of the cutter. The hanger T, which receives motion from the traveler, has connected with it the pusher or pushing part T' proper, (see Fig. 3,) said part being adapted to the shape of the upper face of the trough U, so as to slide freely thereon and prevent the escape of the article to be fed behind said pusher T'. The vertical portion of the pusher is open or separated, forming teeth, between which are passed the tines of the fork T², on which the article to be fed is impaled, thus preventing the rotation or improper displacement of said article, while, however, not interfering with the advance motions of the same by the action of the pusher. The tines are supported on the rear end of the trough and passed through slots therein and provided with a handle T³ for evident purposes. It will be noticed that two rods or shafts are employed for supporting the traveler, and each is provided with an annulus, one of said rods being stationary, as has been stated. Now when the movable rod is returned it passes freely through the annulus thereon, but the other annulus, which is on the stationary rod, bites the latter and so prevents return of the traveler with said movable rod.

Having thus described my invention, what I claim as new, and desire to secure by Letters Patent, is—

1. A smoothly-surfaced shaft, means for imparting reciprocating motions thereto, a traveler freely mounted on said shaft, an obliquely-arranged annulus carried by said traveler and

loosely fitted on said shaft, and means for forcing said annulus into engagement with said shaft.

2. A movable shaft, means for operating the same in opposite directions, a traveler freely mounted on said shaft, an obliquely-arranged annulus carried by said traveler and means for forcing said annulus into engagement with said shaft, in combination with a stationary shaft having an obliquely-arranged annulus loosely fitted thereon and carried by said traveler and provided with means for forcing it into an engagement with said secondary shaft.

3. A sliding shaft, a rotating member, reversely-pitched cams on said member adapted to impart reciprocating motion to said shaft, a traveler freely mounted on said shaft, an obliquely-arranged annulus carried by said traveler and loosely fitted on said shaft, and means for forcing said annulus into engagement with said shaft.

4. A shaft, means for imparting reciprocating motion thereto, a traveler freely mounted on said shaft, an obliquely-arranged annulus carried by said traveler and loosely fitted on said shaft, means for forcing said annulus into engagement with said shaft, and a lever pivoted on said traveler and adapted to engage a side of said annulus for releasing the latter of engagement with said shaft.

5. A shaft, a support therefor, means for imparting reciprocating motion to said shaft, a traveler independently mounted on said shaft, an annulus carried by said traveler and freely fitted on said shaft and a spring bearing against said annulus, said traveler having a shoulder with which one side of the annulus abuts, whereby said annulus is adapted to engage in oblique direction with the surface of said shaft.

6. A movable shaft, a traveler mounted thereon, an obliquely-arranged annulus carried by said traveler and freely fitted in said shaft, and means for forcing said annulus into engagement with said shaft, in combination with cams adapted to engage said shaft in opposite directions, a rotating member on which said cams are supported, and a bolt engaging said cams whereby they are adjusted toward and from each other.

7. A frame having the bolt E' projecting therefrom, in combination with a sliding shaft on said frame and means for advancing the same, a traveler on said shaft, an annulus on said carrier adapted to engage said shaft and a lever carried by said traveler and adapted to engage the side of said annulus, said bolt being in the path of said lever and engaging said lever when the traveler approaches the ends of its course whereby said annulus is released and its biting action and the feeding motion are automatically stopped.
